UNITED STATES PATENT OFFICE.

JACOB H. CARVER, OF NEW YORK, N. Y.

DESIGN FOR A CHART-CASE.

SPECIFICATION forming part of Design No. 34,259, dated March 26, 1901.

Application filed February 27, 1901. Serial No. 49,175. Term of patent 14 years.

To all whom it may concern:

Be it known that I, JACOB H. CARVER, a citizen of the United States, residing in the city of New York, borough of Manhattan, county of New York, and State of New York, have invented and produced a new and original Design for Chart-Cases, of which the following is a specification, reference being had to the accompanying drawings, forming a part thereof.

Figure 1 is a plan view of a chart-case, showing my design. Fig. 2 is an end elevation of the same.

As shown in the drawings, the leading features of my design are the two cylinders A 15 B, connected by the rib or fin C, which latter is provided with the openings D. The cyl-

inders and rib are hollow, the hollows communicating with each other, and their ends are open.

Having described my invention, what I claim, and desire to secure by Letters Patent, is—

The design for a chart-case, as herein shown and described.

In testimony whereof I have signed my name to this specification this 18th day of February, 1901.

JACOB H. CARVER.
